US00D792662S

(12) **United States Design Patent** (10) Patent No.: **US D792,662 S**
Chen (45) Date of Patent: **** Jul. 18, 2017**

(54) **PET DRYER**

(71) Applicant: **Billy Chen**, Baldwin Park, CA (US)
(72) Inventor: **Billy Chen**, Baldwin Park, CA (US)
(**) Term: **15 Years**
(21) Appl. No.: **29/566,367**
(22) Filed: **May 27, 2016**

(51) LOC (10) Cl. **30-99**
(52) U.S. Cl.
USPC **D30/158**

(58) **Field of Classification Search**

CLAIM

I claim the ornamental design for a pet dryer, as shown and described.

DESCRIPTION

FIG. 1 is a perspective view of a pet dryer, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

1 Claim, 4 Drawing Sheets

US D792,662 S
